ATTORNEY.

UNITED STATES PATENT OFFICE.

LEMBERT W. COPPOCK, OF MARION, INDIANA, ASSIGNOR TO COPPOCK MOTOR CAR COMPANY, OF MARION, INDIANA, A CORPORATION OF INDIANA.

STARTER FOR COMBUSTION-ENGINES.

No. 888,226.

Specification of Letters Patent.

Patented May 19, 1908.

Application filed April 4, 1907. Serial No. 366,366.

To all whom it may concern:

Be it known that I, LEMBERT W. COPPOCK, of Marion, county of Grant, and State of Indiana, have invented a certain new and useful Starter for Combustion-Engines; and I do hereby declare that the following is a full, clear, and exact description thereof, reference being had to the accompanying drawings, in which like letters refer to like parts.

10 The object of this invention is to provide an improved means for starting gas, gasolene or other explosive engines.

The chief feature of this invention consists in the provision of a cylinder-like chamber 15 for gasolene and the like mounted in connection with the cylinder of the engine and the provision of a piston that will force a certain amount of the gasolene into the cylinder for starting the same. The piston for doing this work is spring actuated and the valve for closing the entrance into the cylinder is likewise spring actuated so that there is always positive and certain action after the operator has lifted the piston. And normally, while 25 the parts are not in use, the piston closes the inlet into said gasolene chamber and no gasolene flows into the same until the piston is again elevated for starting. Hence, a double means is provided for excluding the gasolene 30 after the engine has been started.

In addition to the foregoing one feature of the invention consists in providing a single means for operating the starting mechanism for a plurality of cylinders.

35 The full nature of this invention will be understood from the accompanying drawings and the following description and claims.

In the drawings, Figure 1 is a plan view of a battery of gasolene engine cylinders, a gasolene tank, the dash-board of an automobile or the like and a handle for operating the starting mechanism, parts, however, being broken away. Fig. 2 is a central vertical longitudinal section through a starting device with the piston elevated and the chamber therein filled with gasolene and the pipe and gasolene tank partly broken away. Fig. 3 is the same with the handle actuated and the gasolene supplied to the engine cylinder. Fig. 4 is a plan view of one of the starting mechanisms shown in Fig. 1. Fig. 5 is a section on the line 5—5 of Fig. 1 showing an indicator on the dash board.

In detail the drawings show a dash board 55 10 of an automobile or the like in front of

which there is a battery of cylinders 11 of gasolene engines and on a higher level than the said cylinders a gasolene tank 12 is provided with a conduit 13 leading therefrom to the starting mechanism associated with each cylinder.

14 is the igniting mechanism.

Upon each cylinder 11 a casing 15 is secured by means of the threaded tubular end 16 screwing into the cap 116. The casing 15 has a cylinder-like chamber 17 adapted to receive gasolene from the tank 12, the conduit 13 being connected with the tubular projection 18 through the box 118. From the chamber 17 in the casing 15 a small passage-way or port 19 extends downward for a slight distance and then enters an enlarged passage-way 20 in the upper end of which a ball-valve 21 is located for closing the passage-way or port 19. This ball valve is held normally closed by the spring 22 which lies in the enlarged passage-way 20.

The upper end of the casing 15 is open and within the upper part of the casing there is a bearing sleeve 23 with suitable packing 24 at its lower end and within this bearing sleeve 23 and the cylinder-like chamber 17 below a piston 25 operates, it being secured upon the piston rod 26 that extends vertically through the cap 27. A spring 28 is coiled about said piston rod between the cap 27 and the piston 25 so as to force said piston downward, as appears in Fig. 3.

The piston rod 26 is elevated by the lever 30 fulcrumed on the pin 31 in the divided arm 32 that is mounted in connection with the casing 15. One end of the lever 30 engages the under side of the disk 33 on the upper side of the piston rod 26 and the other end of the lever 30 is curved downward in the arc of a circle under the eccentric 35 and so as to be actuated by said eccentric. The eccentric 35 is mounted on the rod 36 which extends above the entire battery of gas engine cylinders and has mounted upon it the eccentric 35 for the starting mechanism of every cylinder and it extends through to the rear of the dash 10 and on its rear end there is a crank 37, whereby the operator of the automobile can readily turn the rod 36 and therefore turn all the eccentrics 35 into the position shown in Figs. 2 and 3. Upon the rear surface of the dash 10 a plate 38 is secured having the words "Open" and "Closed" upon it to which a single indicator 39 se- 110

cured on the rod 36 points, so as to show the operator to what position to turn the rod 36 in order to open or close the starting mechanism.

5 In starting the engines the operator turns the crank 37 to bring the indicator 39 to point to the word "Open", as shown in Fig. 5. That brings all of the eccentrics 35 to the position shown in Fig. 2 and through the levers 30 actuated by said eccentrics the pistons 25 are elevated. The suction caused by the elevation of the pistons will bring into chamber 17 a supply of gasoline, but the tank 12 is preferably located on a higher 15 level than the chamber so the gasoline will flow by gravity into said chamber. Then the crank 37 is operated in the opposite direction to bring the pointer 39 to the word "Closed" and that brings all the eccentrics 20 35 to the position shown in Fig. 3 and releases all of the levers 30. Then the springs 25 will force the pistons 25 downward, as shown in Fig. 3, and cause the pistons to force the gasoline in all of the chambers 17 25 out through the ports 19, past the valves 21 and into the cylinders of the gas engines.

What I claim as my invention and desire to secure by Letters Patent is:

1. A plurality of combustion engine cylinders, means mounted in connection with each cylinder for starting the engine, a lever for controlling the starting mechanism for each cylinder, a rotary rod mounted in the means in which the levers for all of the cylinders are fulcrumed, eccentrics on said rods

for actuating said levers, and means mounted on said rod for turning it by hand.

2. The combination with a cylinder of a combustion engine, of a starter provided with a cylinder-like chamber adapted to receive gasoline or the like with a port leading from said chamber into the cylinder, a spring actuated valve for closing said port, a piston in said chamber for forcing gasoline or the like therefrom into said cylinder, a spring for actuating said piston, and means for withdrawing said piston to receive a charge of gasoline or the like.

3. The combination with a cylinder of a combustion engine, of a starter provided with a cylinder-like chamber adapted to receive gasoline or the like with a port leading from said chamber into the cylinder, a spring actuated valve for closing said port, a piston in said chamber for forcing gasoline or the like therefrom into said cylinder, a spring for actuating said piston, a lever engaging the piston rod, an eccentric for actuating said lever, and a rod on which said eccentric is mounted for actuating said eccentric, whereby said piston will be withdrawn to receive a charge of gasoline or the like.

In witness whereof, I have hereunto affixed my signature in the presence of the witnesses herein named.

LEMBERT W. COPPOCK.
